UNITED STATES PATENT OFFICE.

HORATIO G. GILLMOR, OF WASHINGTON, DISTRICT OF COLUMBIA.

RAIL-ANCHOR.

1,306,889.

Specification of Letters Patent. Patented June 17, 1919.

Application filed January 24, 1916. Serial No. 73,894.

To all whom it may concern:

Be it known that I, HORATIO G. GILLMOR, a citizen of the United States, residing at Washington, in the District of Columbia, 5 have invented certain new and useful Improvements in Rail-Anchors, of which the following is a specification.

My invention relates to devices for preventing the longitudinal creep of a railroad 10 rail; and the principal object of the invention is to provide a device which will effectually grip the rail and hold it and at the same time be simple in construction and easily and rapidly applied.

15 A further object of the invention is to provide a rail anchor in which the tendency of the parts to become loosened from vibration or other causes is checked and prevented.

20 A further object of the invention is to provide a rail anchor which will be inexpensive to manufacture, strong and durable and, at the same time, light in weight. Weight is an important consideration both in the cost 25 of manufacture and in the cost of transportation.

One embodiment of the invention is shown in the accompanying drawings, in which:

Figure 1 is a side elevation showing the 30 device in operative position on the rail.

Fig. 2 is a sectional view at the plane indicated by the broken line X X in Fig. 1.

Fig. 3 is a sectional view at the plane indicated by the line X X in Fig. 1 showing a 35 position of the parts when the device is being applied to the rail.

Similar letters refer to similar parts throughout the several views.

In the drawings A designates a portion of 40 a railroad cross tie, which forms a stationary part of the road bed, which supports the rail and over which the rail tends to creep under the well known conditions; and B a railroad rail supported thereon. The rail B is of usual construction comprising a head C a 45 vertical web D and a base flange E. Engaged with the rail B and the cross tie A is the transverse member F of the rail anchor and engaged with the transverse member F or the rail anchor and with the head C and base flange E of the rail B, is the vertical 50 member G of the rail anchor. The transverse member F is constructed with a jaw H arranged to embrace and grip one side of the base flange E of the rail B and with an aperture I in the portion of the member F at

the opposite side of the rail. The end of the member F opposite to the jaw H is provided with a portion K adapted to engage a face of the cross tie A. This tie engaging portion may be inclined so as to engage the cross tie some distance below the rail base E as shown at L in Fig. 1. The end of the member F having the aperture I and the tie engaging portion K is constructed with a portion having a surface M and the corner at 60 which this surface M joins one of the side walls of the aperture I may be rounded as at N. The vertical member G is provided at its upper end with a portion presenting surface O adapted to engage with the under side of the rail head C and at the lower end with a portion P adapted to engage with the surface M of the member F. Connecting the portion P with the body of the member G is a portion Q arranged to traverse the aperture I in the member F and a portion R, which in the operative position of the device 65 engages the upper surface of the base flange E of the rail B at the side opposite to the jaw H of the member F. The member G may be so formed that in the initial condition of G the portion R is slightly bowed or curved as illustrated in Fig. 3, and the relation of the portions P Q and R is such that when the member is placed in the position 70 illustrated in Fig. 3 with the surface O of the member G about to engage with the under surface of the rail head C and the portion Q traversing the aperture I in the member F, the portion P of the member G 75 will engage the surface M of the member F near the point S of the portion P and the portion R of the member G will engage the base flange of the rail near the upper corner of the rail base flange E. The surface O of the member G may be provided by turning 80 the end portion of the material of which G is constructed as illustrated and when this is done the end T presents a convenient striking face.

The rail anchor is applied to the rail by 85 placing the member F with the jaw H in engagement with one edge of the base flange E of the rail B, driving the member F transversely upon the rail until a position is reached exposing sufficiently the aperture I 90 at the other side of the rail base flange E to permit the member G to be inserted in the aperture I and passed to the position shown in Fig. 3. In this position the end 95 S of the portion P of the member G will en- 100

gage the surface M of the member F and the portion R of the member G will engage the upper corner of the rail base flange E while the surface O of member G will just begin to engage the under surface of the rail head C. To get the parts into the operative position shown in Figs. 1 and 2 the upper portion of the member G is forced transversely of the rail from the position illustrated in Fig. 3 either by striking the face T with a hammer to drive it or by applying force to the upper part of the member G in some other suitable manner. The engagement of the upper end of the member G with the under surface of the rail head C produces a camming action which, during this forced transverse movement of the upper end of the member G, forces this portion of the member G downward. The portion R of the member G is pivoted on the upper corner of the rail base flange E and the first effect of the downward movement of the upper portion of the member G is to cause the portion Q to bear upon the transverse member F at N and exert a transverse pull upon the member F and to cause the portion P of the member G, engaging the surface M of the member F at S to press upwardly upon the member F. There is exerted in this way both a transverse pull and an upward pressure of the member G upon the transverse member F. These pressures increase as the parts are forced into position and, in the operative position of the parts illustrated in Figs. 1 and 2, the portion P of the member G engages and presses upwardly upon the surface M of the member F for practically its whole length and the portion Q engages and presses outwardly upon the member F at N.

The forces which are applied to G to cause the portions P and Q to press vertically and transversely upon the member F are, as stated above, the result of the coaction of the upper end of the member G and the under surface of the rail head C and they are transmitted through the portion R of the member G which is pivoted or fulcrumed upon the upper corner of the rail base flange E. As the downward force upon the upper end of the member G increases the portion R of the member G is deflected or bent downward into contact with the upper surface of the rail base flange E and in the final operative position shown in Figs. 1 and 2 the portion R of the member G is pressing downwardly upon the upper surface of the base flange E over practically the entire length of the portion R. By giving the portion R of the member G the curved or bent form illustrated in Fig. 3 the pressure of this portion downwardly upon the upper surface of the rail base flange E is distributed over the entire surface of contact of the portion R of the mem-

ber G with the base flange E and its pressure and grip upon the rail increased with a corresponding increase in the efficiency of the device.

The member G is preferably constructed of resilient material and, while the member G is deformed under the stresses to which it is subjected during and after application, its resiliency will cause it to exert, indefinitely, the pressures upon the transverse member F and the rail B.

From the form of the member G and the forces to which it is subjected it will be apparent that, when the parts are in their operative position, the resiliency or spring action of the member G will tend to cause it to resume the form which the member G has in its unstressed condition and that this will tend to cause the portion of the member G which is vertical or nearly so and wedged in between the undersurface of the head C and the upper surface of the base flange E to move upwardly. The engagement of the surface O of the member G with the under surface of the rail head C prevents this movement and the parts are in this manner effectually locked in position upon the rail and prevented from being accidentally dislodged or loosened upon the rail.

Should it be desired to remove the anti-creeper from the rail it is necessary to forcibly move the upper portion of the member G outward from the rail until the position illustrated in Fig. 3 is reached. This may be done by driving a wedge in between the upper portion of the member G and the web D of the rail or by applying the tool ordinarily used by track mechanics for pulling rail spikes between the web D of the rail and the upper portion of the member G and prying the upper portion of G out from the rail.

While I have described the invention as embodied in a preferred construction, modifications might be made without departure from the principles of the invention. Therefore, I do not wish to be understood as limiting the invention to the particular construction, arrangement and devices shown and described, except so far as these limitations are specifically set forth in certain of the claims herein.

I claim and desire to secure by Letters Patent:

1. A part for anticreepers; comprising a resilient bar constructed to engage the under surface of the head and upper surface of the base flange at one side of the rail base and to engage a seat on the under side of a transversely disposed member below the rail base flange and exert transverse and vertical pressure on said member.

2. A part for rail anchors, comprising a spring constructed to engage a bearing upon the under side of a rail base engaging ele-

- ment and arranged to be forced in between the head and base flange of the rail.
3. A part for anticreepers, comprising a bar of substantially uniform section so formed that, when the lower end of said bar engages a seat upon the lower side of an element in transverse relation to the rail and an intermediate portion fulcrums upon the rail base edge, the upper end may be forced into engagement with the lower surface of the rail head.
4. A part for anticreepers, comprising a bar constructed to engage, at one side of and below the rail base, a seat upon the under side of a transversely disposed member beneath the rail and arranged to be forced into engagement with the under side of the head and the upper surface of the base flange of the rail by forced angular movement of the upper portion of said bar in relation to the rail and distortion of the lower portion thereof.
5. An anticreeper part comprising a resilient bar arranged to engage the under surface of the head and the upper surface of the base flange of a rail, the base flange engaging portion being initially curved upwardly from the base flange and arranged to be forced downwardly into contact with the rail base.
6. An anticreeper comprising a transverse member constructed with a jaw adapted to engage one edge of a rail base flange and a vertically disposed aperture beyond the rail base edge opposite said jaw and a vertically disposed resilient member traversing the aperture in said transverse member and arranged to be driven in between the under surface of the head and the upper surface of the base flange of a rail.
7. The combination with a cross tie and a railroad rail having a head and a base flange, of an anticreeper comprising a transverse element engaging the cross tie and one edge and the bottom of the rail base flange and provided with an aperture beyond the other edge of the base flange and a resilient bar constructed to engage the aperture in said transverse element below the rail base and to be forced in between the head and the base flange above the rail base flange.
8. A rail anchor, comprising a transverse element engaging the rail base at one side of the rail, a vertical element engaging a seat upon the under side of said transverse element at the other side of the rail and fulcrumed upon the corner of the rail base flange, means for straining said vertical element, and means for locking said vertical element in position.
9. An anticreeper, comprising a transverse member provided with a tie abutment and arranged to engage the rail base at one side of the rail and having a seat on the under side thereof at the other side of the rail,
- a vertically disposed member fulcrumed upon the corner of the rail base and engaging said seat in said transverse member, means for subjecting said vertically disposed member to stress and means for locking said vertically disposed member in position.
10. A device for preventing the creeping of rails, comprising a transverse member having means at one end thereof for engaging one side of the rail base and a seat on the under side of the other end thereof, a spring fulcrumed on the upper corner of the rail base and engaging the seat upon said transverse member, means for subjecting said spring to stress, means for locking said spring in position, and means for giving one of said parts a fixed position in the roadbed in opposition to the tendency of the rail to creep.
11. An anticreeper for rails, comprising a vertically extending bar engaging the head and base of the rail at one side of the rail, and a transversely extending part provided with a seat on the under side of one end thereof engaging said vertically extending bar and with means on the other end thereof for so engaging the opposite edge of the rail base as to subject said vertically extending bar to a bending strain.
12. A rail anchor, comprising a bar constructed with a jaw at one end arranged to engage one edge of the rail base flange and provided at the other end with a tie abutment and an aperture and on the under side and beyond said aperture with a seat, a part arranged to traverse said aperture and engage said seat and to extend upwardly and inwardly and engage the head and base flange of the rail and to exert transverse and vertical pressure upon the rail to effect the gripping action.
13. An anticreeper, comprising a part adapted to embrace one side of the base flange of a rail engaging the top and extending transversely beneath the bottom thereof and a spring engaging said member below and the head and base flange of the rail above the base for effecting the gripping action.
14. An anticreeper, comprising a transverse bar having means for engaging the edge of the rail base at one side of the rail and having a seat on the underside of said bar at the other side of the rail and a spring engaging said seat and the other side of the rail provided with a portion which engages the head and the base of the rail to effect the gripping action.
15. A rail anchor, comprising a part arranged for transverse disposition beneath a rail base and constructed with a jaw at one end to engage one edge of a rail base flange and at the other end a tie abutting portion and an aperture, means engaging said aperture in said transverse part below the rail

- and the head and base flange of the rail to effect the gripping action of said anchor.
16. A rail anchor, comprising a transverse member having a tie engaging portion, an abutment engaging one side of the rail, an aperture and a seat on the under side of said member at the other side of the rail, and a spring which engages said seat the corner of the rail base and the head of the rail and holds the rail against creeping.
17. An anticreeper, comprising a part engaging one side of a rail base flange and extending transversely below the rail and a member engaging said part at the other side of the rail and constructed with portions adapted to engage the under side of the head and the upper surface of the base flange, the base flange engaging portion being initially curved upward and forcibly bent down into contact with the base flange.
18. A rail anchor comprising a part having a rail head and an initially upwardly curved base flange engaging portion and a portion extending downwardly at one side of the rail base flange and means for engaging the opposite side of the base flange and said part which subjects said part to a bending strain and causes the initially curved portion to bear with increased pressure upon the rail.
19. An anticreeper provided with means for giving it a stationary position with respect to the roadbed and with rail clamping means, comprising an element having an initially curved portion adapted to be brought into engagement with the upper surface of the rail base by forces exerted thereon from a wedging action of another portion of said element upon the under side of the rail head.
20. A rail stay, comprising a rail embracing and gripping member provided with a jaw adapted to engage one edge of a rail base and at the other end a cross tie engaging abutment, an aperture and a seat, a part engaging said seat and traversing said aperture extending upwardly and inwardly above the rail base with a curvature which will hold said part normally out of contact with the rail base except at the upper corner thereof and means for engaging the rail head and putting downward pressure upon said part whereby it is forced into contact with the upper surface of the rail base and exerts a transverse and vertical pressure upon said member.
21. A device for preventing the creeping of rails provided with means for giving it a stationary position in the roadbed, comprising co-engaging members, one of which is resilient, engages the upper corner of the rail base flange, the rail head and a seat on the under side of the other of said members, said members interlocking and exerting transverse and vertical gripping pressure upon the rail.
22. A rail anchor, comprising a transversely disposed part arranged to be held in fixed position in the roadbed and provided with means for engaging one edge of the base flange of the rail and arranged to extend beyond the other edge of the rail with an aperture in said extended portion, and a spring adapted to engage said aperture and the rail head and provided with an initially upwardly curved portion which is flattened out to engage the upper surface of the rail base.
23. An anticreeper, comprising a transversely extending part provided at one end with means for engaging the edge of the rail base flange at one side of the rail and at the other end with an aperture and a seat on the under side thereof adjacent to the opposite edge of the rail base, and a vertically disposed spring constructed to traverse the aperture and engage a seat upon the under side of said transversely extending part and to be driven in between the head and base flange of the rail to effect the gripping action.
24. In a rail anchor, the combination of a rail embracing element and a spring provided with a curved portion adapted to be flattened out into engagement with the upper surface of the rail base by a wedging action between the rail head and said spring, whereby the said spring when in operative position is caused to press upon the upper surface of the rail base.
25. In a rail anchor, the combination of a rail embracing element and rail engaging means intervening between the rail head and one end of said rail embracing element comprising a spring member which is formed with a curved portion which is forced against and presses upon the upper surface of the rail base.
26. An anticreeper comprising a transverse member provided with means for giving said member a stationary position with respect to the roadbed having a jaw adapted to engage one edge of a rail base flange and a vertically disposed aperture beyond the rail base opposite said jaw and a vertically disposed resilient member traversing the aperture in said transverse member and arranged to be driven in between the under surface of the head and the upper surface of the base flange of the rail.
27. In a rail anchor, the combination of a rail embracing element provided with a tie abutting flange and with a jaw extending around one edge of the rail base and a resilient part engaging a seat on the under side of said rail embracing element and intervening between the rail head and the upper surface of the rail base.

28. A rail anchor comprising a part provided with means for giving it a stationary position in the roadbed and adapted to embrace one side of the base flange of the rail engaging the top and extending transversely beneath the bottom thereof and a spring engaging said part below and the head and base flange of the rail above the base for effecting the gripping action.
- 10 29. A device for preventing the creeping of rails comprising an element engaging one side of the rail base flange and extending transversely beneath the rail and provided with means for giving said member a fixed position in the roadbed and a part engaging said element at the other side of the rail constructed with portions adapted to engage the under side of the head and the upper surface of the base flange, the base flange engaging portion being initially curved upward and forcibly bent down into contact with the base flange.
- 15 30. A rail anchor comprising a part having a rail head engaging portion and an initially upwardly curved base flange engaging portion and a portion extending downwardly at one side of the rail base flange, means for engaging the opposite side of the base flange and said part which subjects said part to a bending strain and causes the initially curved portion to bear with increased pressure upon the rail and means for giving said anchor a fixed position in the roadbed in opposition to the tendency of the rail to creep.
- 20 31. A rail anchor provided with rail clamping means comprising a transversely
- disposed element engaging the rail base at one side and a tie at the other side of the rail in opposition to the tendency of the rail to creep and a spring which engages said element and the rail base edge and is forced in between the head and base flange of the rail.
- 25 32. An anticreeper provided with rail clamping means comprising co-engaging members one of which is transversely disposed in relation to the rail and engages the base at one side and a tie in opposition to the tendency of the rail to creep at the other side of the rail and the other of which is a spring engaging said transversely disposed member and the under side of the rail head.
- 30 33. A device for preventing the creeping of rails provided with rail clamping means comprising co-engaging elements one of which engages the rail base at one side of the rail extends transversely beneath the rail and engages a tie in opposition to the tendency of the rail to creep at the other side of the rail and the other of which elements engages the rail head and is provided with a resilient portion engaging the upper surface of the rail base.
- 35 34. A rail anchor comprising co-engaging elements one of which is resilient and provided with rail head and base flange engaging portions and one of which engages the rail base at one side of the rail and a tie in opposition to the tendency of the rail to creep at the other side of the rail, said members interlocking and exerting transverse and vertical gripping pressure upon the rail.
